UNITED STATES PATENT OFFICE.

HARRY S. HART, OF CHICAGO, ILLINOIS, ASSIGNOR TO NATIONAL DUMP CAR CO., OF CHICAGO, ILLINOIS, A CORPORATION OF MAINE.

DUMP CAR.

1,425,767.

Specification of Letters Patent. Patented Aug. 15, 1922.

Application filed August 4, 1921. Serial No. 489,701.

To all whom it may concern:

Be it known that I, HARRY S. HART, a citizen of the United States, residing at Chicago, in the county of Cook and State of Illinois, have invented certain new and useful Improvements in Dump Cars, of which the following is a specification.

This invention relates to a new and improved general service car, and more specifically to door locking mechanism for such cars.

General service cars comprise fixed ends and sides, and floors consisting of a plurality of downwardly swinging doors. It has been the general practice to place a pair of doors one on either side of the center sill between each adjacent pair of cross bearers. However, in certain forms of cars, where cross-bearers are relatively widely spaced, it has been found desirable to place a pair of doors side by side on either side of the center sills and between each adjacent pair of cross bearers. The locking mechanism in common use for such general service car doors comprises a longitudinally extending locking shaft which is adapted to be moved laterally of the car to bring it under the free end of the doors, thus holding the doors locked. When moved laterally in the reverse direction, the shaft clears the door ends, which drop down by gravity to the open position. These longitudinal door shafts have been very generally supported only in the cross bearers, slots of suitable length and inclination being provided so that the lateral movement of the shaft is permitted. Where a single door is provided between adjacent cross bearers, the door has been supplied with bearing members adapted to bear upon the locking shaft immediately adjacent the cross bearers. The portion of the shaft between each pair of cross bearers may be considered a beam supported at each end and with the load applied immediately adjacent the supports, it is not necessary for the shaft to be of great size or strength. However, with the new form of paired doors, one-quarter of the load is applied adjacent each support, while the remaining half of the load is applied at the center of the beam. This form of loading, even with the same total load, requires a beam of considerably greater strength.

It is an object of the present invention to provide in connection with general service

cars having a plurality of doors between adjacent cross bearers, means for supporting the door locking shaft intermediate the cross bearers.

It is a further object to provide supporting means which are simple in design and which may be readily applied at small cost.

It is also an object to provide supporting means which will not interfere with the discharge of material from the car.

Other and further objects will appear as the description proceeds.

My invention, in the embodiment selected for illustration, comprises the application of supporting means intermediate the cross bearers, this supporting means comprising a clip attached to the car side and extending inwardly between the adjacent doors. The clip is provided with a slot adapted to receive the door shaft and to support it therein. This results in breaking that portion of the shaft between adjacent cross bearers into two short beams, and the loads are then applied immediately adjacent the ends of the short beams. This permits the use of a locking shaft as light or lighter than that heretofore in use, where single doors are placed between adjacent cross beams.

I have illustrated a preferred embodiment of my invention in the accompanying drawings, in which

Figure 1 is a fragmentary plan view of a general service car showing my invention applied thereto;

Figure 2 is a side elevation of Figure 1; and

Figure 3 is a section taken on line 3—3 of Figure 2.

Referring to the figures, the car comprises the ends 4, sides 5, center sills 6 and cross bearers 7. As best shown in Figure 1, a pair of doors 8 is provided between each pair of cross bearers 7. These doors are hinged at 9 adjacent the center sills, and their outer ends are free to swing downwardly.

The outer ends of the doors are provided with bearing members 10 adapted to engage the lock shaft 11. This lock shaft 11 is provided at the cross bearers with toothed wheels 12 engaging racks carried by the cross bearers. Lateral movement is thus given the shaft when it is rotated.

The clip 13 is attached to the car side at 14 and is provided with the portion 15 ex-

tending under the car floor. This portion 15 is provided with the slot 16 through which the shaft 11 is passed. It will be noted that the portion 15 extends but a short 5 distance beyond the ends of the doors, and since the member is relatively thin, there will be practically no obstruction to the passage of material from the car when the doors are open.

- 10 As best shown in Figure 2, the shaft 11 is thus supported intermediate the cross bearers 7 and the load from the doors 8 is transmitted to the shaft by members 10 adjacent the clip 13 and also adjacent the bearers 7. 15 A comparatively light shaft will thus easily take care of the load. The shaft 11 is rotated by means of suitable mechanism such as that shown in my Patent No. 1,318,444, granted October 14, 1919, for door operating mechanism, which operating mechanism, however, forms no part of the present invention and has not been shown.

I claim:

1. In a car having a plurality of doors located between adjacent cross bearers, a door locking shaft adapted to engage the free ends of the doors, and means supporting said locking shaft intermediate the cross bearers.
2. In a car having a plurality of doors located between adjacent cross bearers, a door locking shaft, said shaft extending longitudinally of the car and transversely of the doors and adapted in the locked position to support the free ends of the doors, and means supporting said locking shaft intermediate the cross bearers.
3. In a car having a plurality of doors located between adjacent cross bearers, a door locking shaft adapted to engage the free ends of the doors, and means supporting said locking shaft intermediate the cross bearers, said means being located intermediate adjacent doors.
4. In a car having a plurality of doors

located between adjacent cross bearers, a door locking shaft, said shaft extending longitudinally of the car and transversely of the doors and adapted in the locked position to support the free ends of the doors, and clips attached to the car side and having inwardly extending portions provided with slots adapted to receive and support the door locking shaft, said clips being located intermediate adjacent cross bearers.

5. In a general service car having a plurality of downwardly opening doors interposed between each pair of adjacent cross bearers, a longitudinally extending locking shaft adapted to be moved laterally under the free ends of the doors to support said doors in the locked position and to be moved laterally in the reverse direction for unlocking said doors, said shaft being supported in the cross bearers, and additional supports for said shafts located intermediate the cross bearers.

6. In a general service car having a plurality of downwardly opening doors interposed between each pair of adjacent cross bearers, a longitudinally extending locking shaft adapted to be moved laterally under the free ends of the doors to support said doors in the locked position and to be moved laterally in the reverse direction for unlocking said doors, said shaft being supported in the cross bearers, and clips attached to the car side and having inwardly extending portions provided with slots adapted to receive and support the door locking shaft, said clips being located intermediate adjacent doors and spaced from the cross bearers.

7. A car having an underframe comprising cross bearers, a plurality of doors between adjacent cross bearers and means of supporting the adjacent edges of the doors directly from the car frame.

Signed at Chicago, Illinois, this 26th day of July, 1921.

HARRY S. HART.
